DESIGN FOR A SHOE OR SIMILAR ARTICLE

Schuyler A. Wood, Dolgeville, N. Y.

Application September 23, 1937, Serial No. 71,755

Term of patent 3½ years

To all whom it may concern:

Be it known that I, Schuyler A. Wood, a citizen of the United States, residing in Dolgeville, in Herkimer County, in the State of New York, have invented a new, original, and ornamental Design for a Shoe or Similar Article, of which the following is a specification, reference being had to the accompanying drawing, forming part thereof.

I claim:

The ornamental design for a shoe or similar article, substantially as shown.

SCHUYLER A. WOOD.
